UNITED STATES PATENT OFFICE.

PETER GENDRON, OF TOLEDO, OHIO.

EXPANDING REAMER.

SPECIFICATION forming part of Letters Patent No. 289,248, dated November 27, 1883.

Application filed January 22, 1883. (No model.)

To all whom it may concern:

Be it known that I, PETER GENDRON, of Toledo, in the county of Lucas and State of Ohio, have invented new and useful Improvements in Expanding Reamers; and I hereby declare that the following is a full, clear, and exact description thereof, reference being had to the accompanying drawings, which form a part of this specification.

10 This invention relates to certain new and useful improvements in the construction of expanding reamers; and the invention consists in the peculiar construction and arrangement of the knives or cutters within the head and the means employed for securing them in their adjustable positions, all as more fully hereinafter set forth.

Figure 1 is a central vertical longitudinal section through my improved device, and Fig. 20 2 is a cross-section of the same.

In the accompanying drawings, A represents the shank, which is provided with the enlarged head B, and with the threaded stud C at the outer end.

25 D represents the cutters, which are designed to fit snugly in longitudinal inclined channels cut in the periphery of the head B, the knives gradually increasing in thickness from point to heel, with parallel sides, while 30 their inner ends are beveled off and enter the collar or sleeve E, which slips over the shank and is retained in its proper position by the nut F, which is screwed upon the shank, the latter being threaded for that purpose. Upon the 35 outer and threaded end, C, of the shank, I secure a supporting-nut, G, and the nut H. The inner face of this nut H is slightly conically recessed, and has formed in it the radial channels a, which are brought coincident with the longitudinal channels in the head, and are 40 designed to receive the outer or toe end of the cutters, which are slightly beveled or chamfered off, so that they will fit snugly into such recesses or channels a. In practice, when the 45 cutters are retracted so as to perform their function within their smallest diameter, the greater portion of them is retained within the channels in the head, being securely locked to place at toe and heel by the collar E and

nut F at one end and the nut H at the outer 50 end.

It has been found in expanding reamers where the cutters are projected beyond a certain distance from the head there is no support for the outer or toe end of the cutters, and hence 55 they very often break. In my device, when the cutters are projected from the head to any extent, a supporting-nut is so adjusted that the outer ends of the cutters will rest upon the periphery of such nut, while the channels in 60 the face of the nut H hold the cutters rigidly to place and prevent any giving from the work. By the use of the tapered channels and cutters of corresponding taper the bottoms of the channels form a firm support for 65 the backs of the cutters under all changes in position, and by making the stock or shank and the ribs in one piece, so as to make said ribs solid with the stock at the bottoms of the channels, there is no liability of said ribs being 70 broken off by the side strain to which they are subjected when in use, whereas if the shank or stock were made solid, with a tapering base sliding therein, as has heretofore been proposed, the ribs are only connected to 75 each other at the top and bottom, and are thus easily broken.

I am aware of the Patents Nos. 71,339, 111,296, and 252,903, and make no claim to anything shown therein.

80 What I claim as my invention is—

1. In an expanding reamer, the combination, with the cutter-stock, consisting of the stock A and head B, having a series of ribs formed thereon, said stock, head, and ribs being in one piece, and the ribs forming radiating channels tapering from end to end, of a series of tapering cutters resting on the bottom of said channels, and means, substantially as described, for securing both ends of 90 said cutters to the head, as set forth.

2. In an expanding reamer, the combination, with the cutter-stock, consisting of the stock A and head B, the latter having a series of ribs formed integral therewith and radiating therefrom, forming channels tapering from end to end, of the nut F, collar E, tapering cutters D, resting on the bottom of said

channels, and dished nut H, substantially as described.

3. In an expanding reamer the cutter-stock of which consists of the shank A and head B, the latter having a series of ribs formed integral therewith and radiating therefrom, forming channels tapering from end to end, taper cutters D, resting on the bottom of said

channels, collar or sleeve E, nut F, supporting-nut G, and retaining-nut H, all constructed, arranged, and operating substantially as and for the purpose set forth.

P. GENDRON.
